UNITED STATES PATENT OFFICE.

ELBERT GRIFFIN, OF TERRE HAUTE, INDIANA.

DESIGN FOR A PANEL FOR FURNITURE.

Application filed March 1, 1928. Serial No. 25,638. Term of patent 7 years.

To all whom it may concern:

Be it known that I, ELBERT GRIFFIN, a citizen of the United States, residing at Terre Haute, in the county of Vigo and State of Indiana, have invented a new, original, and ornamental Design for a Panel for Furniture, of which the following is a specification, reference being had to the accompanying drawing, forming part hereof, in which the figure is a perspective view of the article, showing my new design.

I claim:

The ornamental design for a panel for furniture, as shown.

In witness whereof, I have hereunto set my hand at Terre Haute, Indiana, this 27th day of February, A. D. nineteen hundred and twenty-eight.

ELBERT GRIFFIN.
